UNITED STATES PATENT OFFICE.

LOUIS T. PYOTT, OF PHILADELPHIA, PENNSYLVANIA.

DRIVING DEVICE FOR METAL-PLANERS.

SPECIFICATION forming part of Letters Patent No. 273,150, dated February 27, 1883.

Application filed November 9, 1882. (No model.)

To all whom it may concern:

Be it known that I, LOUIS T. PYOTT, a citizen of the United States, residing at Philadelphia, in the county of Philadelphia and State of Pennsylvania, have invented a new and useful Improvement in Driving Devices for Metal-Planers, of which the following is a specification.

My invention relates to a driving device for imparting to the table of a metal-planing machine a traversing movement; and it consists of two vertical shafts provided with pinion-wheels, which latter gear into double horizontal racks bolted centrally to the under portion of the planer-table. The lower ends of said vertical shafts are provided with worm-wheels, which gear into right and left worms placed upon the drive-shaft; and also in adapting the usual support or legs, as placed under the center of the bed, to form bearings and casings for the driving attachment, said casings being bolted to the lower flanges of the bed. The screw or driving shaft is placed transversely to the planer, thus allowing the actuating-pulleys to revolve in the same direction as in the ordinary planer, requiring a less complicated device to reverse the movement of the table, which is a decided advantage in the arrangement of the mechanism for producing short strokes. The double horizontal racks affording increased wearing-surface, less accuracy is required in adjusting relations of table and bed. The driving mechanism is protected from dust and grit at top by means of guards, and at bottom by the casing or frame, which is supplied with cavities containing oil for lubrication.

In the accompanying drawings I have represented my driving mechanism attached to an ordinary metal-planer, having a reciprocating movement imparted to the table or carriage by means of my driving device.

Figure 1 is a transverse section on the line 1 1, Fig. 2. Fig. 2 is a side elevation. Fig. 3 is a plan from beneath.

1 1 are upright frames, connected at the top by a tie or cross-beam, 2, and bolted at the bottom to the upper flanges, 3 3, of the bed-plate 4.

5 5 is the reciprocating table, moving in V-slides 6 6.

7 7 are pinion-wheels, which gear into horizontal racks 8 8. Said pinion-wheels are placed on vertical shafts 9 9, which latter are provided at their lower ends with worm-wheels 10 10, gearing into right and left worms 11 and 12, situate on a horizontal driving-shaft, 13.

14 14 are actuating-pulleys, and 15 is a loose pulley.

16 16 are guards at top, and 17 is the casing or frame, bolted to the lower flanges, 18 18, of the bed-plate 4.

19 19 are gear-supports cast with casing or frame 17.

The principle of operation is as follows: 6 6 Power being applied to the actuating pulley or pulleys 14 14, the horizontal driving-shaft 13 is rotated, and with it the right and left worms 11 and 12, which respectively cause the worm-wheels 10 10 to revolve in opposite directions. This movement is communicated, by means of the vertical shafts 9 9, to the pinion-wheels 7 7, which in turn, by gearing into the racks 8 8, impart to the table 5 a reciprocating movement in its guide 6 6. The driving-shaft 13, being situate transversely to the planer, allows the actuating-pulleys 14 14 to be placed in the same position as in the ordinary planer—viz., at the side thereof—thus requiring a less complicated device to reverse the movement of the table 5 than if placed at the end.

Having thus described my invention, what I claim as new, and desire to secure by Letters Patent, is—

1. The combination, in a metal-planing machine having table 5, of the racks 8 8, pinion-wheels 7 7, and worm-wheels 10 10 on the vertical shafts 9 9, and right and left worms 11 and 12 on the transverse driving-shaft 13, for the purpose set forth.

2. The combination, in a metal-planing machine and its driving mechanism, of the frame or casing 17 and gear-supports 19 19, the said frame and supports being cast in one piece, substantially as and for the purpose set forth.

LOUIS T. PYOTT.
